CLAIM

The ornamental design for an infrared sensing device, as shown and described.

DESCRIPTION

FIG. 1 is a perspective view of an infrared sensing device of the present invention;
FIG. 2 is a top view thereof;
FIG. 3 is a bottom view thereof;
FIG. 4 is a front view thereof;
FIG. 5 is a rear view thereof;
FIG. 6 is a left side view thereof;
FIG. 7 is a right side view thereof; and,
FIG. 8 is a cross-sectional view thereof taken along lines 8-8 of FIG. 2.
